Attorney, Agent, or Firm—Marshall, O'Toole, Gerstein,
Murray & Borun[57] **CLAIM**

The ornamental design for a brush handle, as shown and described.

DESCRIPTION

FIG. 1 is a left-side view of a brush handle showing my new design;

FIG. 2 is a front elevational view thereof;

FIG. 3 is a right-side elevational view thereof;

FIG. 4 is a rear elevational view thereof;

FIG. 5 is a top plan view thereof;

FIG. 6 is a bottom plan view thereof; and,

FIG. 7 is a plan view along the line 7—7 of FIG. 1.

The bristles shown in dotted outline in the drawings are for illustrative purposes only and form no part of the claimed design.
